CINCINNATI, OHIO.

Design No. 4,960, dated May 30, 1871.

DESIGN FOR IRON MANTELS.

The Schedule referred to in these Letters Patent and making part of the same.

We, CALEB B. EVANS, JOHN CARLISLE, and GRANT H. BURROWS, of Cincinnati, in the county of Hamilton and State of Ohio, have invented and produced a new and original Design for Iron Mantels, of which the following is a specification.

The nature of our design is fully represented in the accompanying illustration, to which reference is made.

In the illustration No. 3 the shelf A has on its outer edge a heavy molding consisting of two members.

The most of the front edge is, in plan, a reversed curve, swelling out furthest at the center *a*.

The ends, *b*, which are straight for a short distance, have a trend at an angle of forty-five degrees, or thereabout, with the face of the mantel.

The ends of the mantel-shelf are recessed at *c*.

The edge of the circular grate-opening of the face B of the mantel is chamfered off, as are also the upper and inner corners of the pedestals C, which are in the form of parallelograms, without ornament, and are surmounted by a double-membered molding.

Two triangular panels, *d*, surrounded by heavy-membered moldings, are located one on each side of the center-piece D. They are, in form, irregular tri-

angles, and cover the larger part of the face of the mantel. Their smaller ends extend down below the springing line of the circular-arched grate-opening.

Above the springing line the panels and their moldings are curved concentrically to the arched grate-opening.

The opposite sides of the panels and their moldings form miters with moldings *e* concave toward the center-piece D.

The center-piece D is in two members. The superior is H-shaped, with curved pillars chamfered off at top and bottom. The inferior member is small and pendulous, its lower end being close to the crown of the arched grate-opening in the face of the mantel.

We claim as our invention—

The design for iron mantels, as shown and described.

CALEB B. EVANS.
JOHN CARLISLE.
GRANT H. BURROWS.
